BATHING SUIT

Filed Aug. 8, 1927

Herbert J. Knapp, INVENTOR
BY Victor J. Evans

ATTORNEY

UNITED STATES PATENT OFFICE.

HERBERT J. KNAPP, OF AKRON, OHIO.

BATHING SUIT.

Application filed August 8, 1927. Serial No. 211,448.

My present invention has reference to a bathing suit primarily designed for use by ladies and which suit is preferably formed of rubberized silk or cotton stockinette which has an outer facing of rubber or like soft and elastic water-proof material, and my primary object is the provision of a detachable skirt of the same material as the suit, one piece bathing suits of this type 10 and wherein the lower or outer edge of the skirt is integrally formed with an inflatable chamber and valve means for inflating the chamber by the user of the suit whereby the skirt may be drawn upwardly over the suit 15 and the chamber thereof serve as a means for buoying the bather in the water in case of fatigue by expert swimmers or as an aid to learners in swimming.

To the attainment of the foregoing the 20 invention consists in the improvement as hereinafter described and definitely claimed.

In the drawings:

Figure 1 is a perspective view illustrating my improvement in applied position. 25 Figure 2 is a sectional view through a portion of the suit approximately on the line 2—2 of Figure 1. Figure 3 is a detail view to illustrate the valve construction. 30 Fig. 4 is a side elevational view of the fastening device, in section. The bathing suit 1 is of the one-piece type, and is preferably formed of rubberized silk or cotton stockinette having an outer facing 35 of rubber or similar water-proof material although the said suit may be of the usual woven or cotton type, as my present invention relates to the skirt for the same.

The skirt is preferably and may have a 40 coating of rubberized material to render the same water-proof although the skirt proper may be of the usual woven type. The skirt at the waist portion thereof is provided with spaced loops 3 for the passage of the belt 45 4, the ends of the belt being connected by the usual buckle 5. In the showing of the drawings, the water-proof skirt 2 has its lower edge folded upon itself to provide the same with a tubular air chamber 6. The air chamber is, of course, constructed of water proof material in the event that the same is not formed upon the skirt of like material. The outer face of the chamber 6, at the center thereof, has cemented or otherwise secured 50 thereto a flexible pipe or hose 7. The air passage through this hose is normally closed

by the said hose being compressed against the outer face of the chamber through the medium of an elastic strap 8 whose ends are fixed to the said outer face of the chamber 60 and through which strap the hose is passed and doubled upon itself after the chamber is inflated. Obviously the expansion of the chamber 6 will stretch the strap so that the hose is compressed against the outer wall of the chamber and the passage of air therethrough is effectively prevented. The strap as disclosed by the drawings is preferably concealed by a rosette preferably of rubber or rubberized material. When the chamber 65 is not inflated the skirt is worn in the usual manner but the said skirt is drawn upwardly over the bathing suit to the position shown in dotted lines in Figure 1 of the drawings and the hose is brought into 70 the mouth of the bather for inflating the chamber 6. The air passage through the hose is sealed in a manner above described so that the chamber 6 is retained inflated for any desired length of time. The improvement may be employed by either expert or amateur swimmers or as a matter-of-fact, by beginners and the device not only provides a one piece bathing suit with a 75 detachable skirt but serves as an aid to expert swimmers and a life preserver for amateurs as well as a means for teaching beginners the art of swimming.

Having described the invention, I claim:

1. The combination with a one-piece bathing suit, of a detachable skirt therefor, a belt fastening the skirt around the suit, said skirt having its outer ends provided with a continuous inflatable chamber, valve means for introducing air from the mouth of the 90 user of the suit into the chamber to inflate the same and means carried by the chamber engageable with such valve means for preventing the passage of air therethrough.

2. The combination with a one-piece bathing suit, of a detachable skirt therefor, of light water proof material, said skirt having spaced loops at the waist thereof for the passage of a sustaining belt therethrough, said skirt having its lower edge folded upon 95 itself but cemented or otherwise secured to the inner face of the said skirt to provide an inflatable chamber, and valve means for inflating the chamber.

In testimony whereof I affix my signature.

HERBERT J. KNAPP.
